STRAND TWISTING APPARATUS

Roland R. Nydegger, Baltimore, Md., assignor to
 Western Electric Company, Incorporated, New
 York, N. Y., a corporation of New York

Application January 10, 1935, Serial No. 1,130

13 Claims. (Cl. 117—46)

This invention relates to strand twisting apparatus, and more particularly to an apparatus for twisting strands together to form a composite group.

The invention is particularly applicable for use in the manufacture of grouped electrical conductors, for example, conductor "quads", i. e., a group of four conductors intended as a component unit of a multi-conductor telephone cable. In the forming of such quads it has been the practice, in some instances, to twist two single conductor strands to form a pair and then twist two such pairs to form a quad. Heretofore, in some cases, each twisted pair and/or quad has been individually bound with a continuous cotton thread helically applied in order, among other reasons, to aid in causing the two conductors of the pair and/or the two pairs of the quad, as the case may be, to be of the same length, which is desirable in the production of quadded cable having the electrical characteristics required. For a complete disclosure of the specific construction and functions of a "quadded cable" reference is made to U. S. Patent to Anderegg and Mougey, No. 1,271,824.

An object of the invention is to provide an improved apparatus for twisting a plurality of strands into a plurality of units, without the referred to binding operation, and while maintaining the length of the strands of each unit the same, twist the units into a single group.

In accordance with one embodiment of this invention as applied to the forming of conductor quads of the hereinbefore described type, there is provided an apparatus comprising means for supplying four electrical conductors, means for grouping the four conductors together in pairs, means for twisting the conductors of each pair together, and twisting together the twisted pairs of conductors to form a quad. Each pair of conductors is moved about a cone-shaped path while moving towards its apex, the individual pair and the quad twists being effected close together and adjacent the apex of the cone-shaped path. The pair twists are formed at a point so near the point of quad formation that the relative positions and thereby the length of twist of the conductors of each pair will remain the same and not be disturbed before they are held by the quad twist. In the preferred embodiment of the invention the motion of the twisting mechanism is entirely continuous.

Other objects and advantages of the invention will more fully appear from the following detailed

description taken in connection with the accompanying drawings, in which

Fig. 1 is a fragmentary side view of one form of a strand twisting apparatus embodying the features of the invention;

Fig. 2 is an enlarged fragmentary view, partly in section, of a portion of Fig. 1;

Fig. 3 is an enlarged fragmentary plan sectional view taken on the line 3—3 of Fig. 2;

Fig. 4 is an enlarged fragmentary central vertical sectional view taken on the line 4—4 of Fig. 2;

Fig. 5 is an irregular central vertical sectional view taken on the line 5—5 of Fig. 4;

Fig. 6 is a fragmentary side view of another embodiment of a twisting apparatus of this invention;

Fig. 7 is a reduced plan sectional view across the entire apparatus taken on the line 7—7 of Fig. 6;

Fig. 8 is an enlarged inverted detail plan sectional view taken on the line 8—8 of Fig. 6, and

Fig. 9 is an enlarged fragmentary plan view taken on the line 9—9 of Fig. 6.

Referring now to the drawings wherein only such portions of the apparatus have been shown which are essential to an understanding of the invention, and particularly to Fig. 1, a portion of the stationary frame of the apparatus is indicated at 10 and journaled thereon is a continuously rotating flier comprising a vertical shaft 11 and spaced aligned horizontal cross bars 12 and 13. Between the ends of the cross bars 12 and 13 at opposite sides of the shaft 11 are rotatable yokes 16 and 17, each yoke having secured to the opposite ends thereof a stud shaft 18 which is journaled in suitable bearings provided in the ends of the cross bars. In the operation of the apparatus the flier comprising the shaft 11 and the cross bars 12 and 13 is rotated by means of meshing beveled gears 19 and 20 secured to the shaft 11 and a driving shaft 23, respectively, the latter shaft being rotated from a suitable source of power (not shown). During the rotation of the flier the yokes 16 and 17 revolve therewith and also rotate on their own axes by means of the following gear train. Secured to the stationary frame 10 and coaxial with the shaft 11 is a gear 24 which at diametrically opposite points meshes with gears 25 secured to the lower ends of the shafts 26 journaled in the cross bar 13, the upper ends of the shafts having fixed thereto gears 27 which mesh with gears 30 secured to the shafts 18 fixed to the lower ends of the yokes 16 and 17. Rotatably supported in any well known

manner upon each of the yokes 16 and 17 is a pair of conductor supply reels 31 and 32, respectively. Insulated conductors 33 and 34 from the supply reels 31 and 32, respectively, are continuously drawn upwardly by a capstan 37 and delivered to a suitable take-up mechanism (not shown).

The conductors 33 and 34 are each subjected to a desired constant tension as they are withdrawn from the reels 31 and 32 by any usual form of tension control desired (not shown). It is to be understood that the capstan 37 is driven in definite relation with the rotation of the filer shaft 11 and the yokes 16 and 17 by means (not shown) so that the proper number 10 of twists per unit length of conductor will be introduced into each pair of conductors 33 and 15 34 to be twisted and into the two pairs of twisted conductors in forming the quad. The details 20 of the mentioned tension control device and means for driving the capstan have been omitted 25 from the disclosure for the sake of simplifying the same, since they form no part of the present invention and are not believed necessary to a complete understanding thereof.

The type of quadded cable for which the apparatus illustrated is set up to produce is one in which the adjacent pairs of twisted conductors 33 and 34 have different lays or lengths of twist and each pair is twisted in a left-hand 30 direction, the direction of the pair twists being indicated by the arrows associated with the yokes 16 and 17 (Fig. 1), and the twists in the quad being shorter than the twists in the pairs constituting the quad, the quad twist being in 35 a right-hand direction, the direction of the quad twist being indicated by the arrow associated with the filer shaft 11. The length of twist put in the individual pairs and the length of the twists between the two pairs may be controlled 40 as desired by the substitution of the proper size gears in the gear train including the pairs of gears 25, 27, 30, 19 and 20.

In the particular set up of the apparatus as shown the conductors 33 are to be twisted with 45 a shorter lay or length of twist than the conductors 34; therefore, in operation the yoke 16 will be rotated at a higher rate of speed than that of the yoke 17.

Between the supply reels and the capstan each 50 pair of traveling conductors 33 and 34 is associated with a mechanism which first groups the conductors into individual pairs, then twists the conductors of each pair together and immediately thereafter maintains the relative positions 55 of the individual conductors of each pair and of each twisted pair relative to the other twisted pair, followed by the immediate twisting of the twisted pairs together to form a quad. Each 60 pair of conductors 33 and 34 in their passage from the supply reels 31 and 32, respectively, up to the point of twisting the twisted pairs into a quad is handled in a similar manner, except for the length of twists put in the individual pairs, and the mechanism associated with each 65 pair of conductors aside from the gear ratio is identical in all particulars, so that a description of one of them, the one associated with the conductors 33 at the left side of Fig. 1, will suffice.

The stud shaft 18 secured to the upper end of 70 the yoke 16 is formed with an axial aperture 38 (Fig. 2), the shaft having fixed to its upper end surface a two-holed polisher 39 (Figs. 2 and 3). A gear 40 provided with an axial 75 shouldered aperture surrounds the polisher 39 and the upper end of the shaft 18, which ex-

tends above the upper surface of the filer frame 12, the gear and the polisher being secured to the shaft 18 for rotation therewith at a uniform speed by screws 41 which pass through apertures in the polisher and are threaded into the 5 upper end surface of the shaft 18. Fixed to the filer cross bar 12 is a bracket 44 supporting directly above the gear 40 a freely rotatable idler sheave 45 which is carried with the filer about the axis of the filer shaft 11. The two conductors 33 continuously drawn from the supply reels 31 are grouped together in parallel spaced relation as they enter the lower end of the aperture 38 of the shaft 18 and pass through the holes of the polisher 39 and are continuously and uniformly twisted in a left hand direction along that portion of the conductors between the polisher and the point of contact of the conductors with the periphery of the idler sheave 45 over which the conductors are drawn as the polisher 20 rotates about its own axis with the yoke 16 while revolving bodily with the filer about the axis of the filer shaft 11.

Mounted upon the upper end of the shaft 11 and secured at 46 (Fig. 2) for rotation therewith 25 is a casting 47. At diametrically opposite points the casting 47 is formed with angularly arranged bearings within each of which is rotatably carried a shouldered shaft 48 formed with a shouldered axial aperture (Figs. 2, 4 and 5). Fixed 30 to rotate with the shaft 48 within an enlarged upper end portion of the aperture of the shaft is a two-holed polisher 51. At its lower end the shaft 48 extends into a recess formed in the casting 47 and has secured thereto a gear 52. 35 The two-holed polisher 51 is driven at the same speed and in the same direction as the two-holed polisher 39 by means of gears 53 and 54 meshing with the gears 40 and 52 fixed to the polishers 39 and 51, respectively, and a universal 40 shaft 55 interconnecting the gears 53 and 54, the arrangement of the gears 53 and 54 relative to the gears 40 and 52 and their ratios being 45 such that the polishers are driven at the same speed and in the same direction. The lower 50 portion of the universal shaft 55 is journaled in a bearing 58 carried upon the filer cross bar 12 and the upper portion of the shaft is journaled in a bearing 59 fixed to the casting 47. Since the two-holed polishers 39 and 51 are 55 driven at the same speed and in the same direction the twists continuously being formed in the pair of conductors 33 between the polisher 39 and the point of contact of the conductors with the periphery of the idler sheave 45 are continuously removed upon the conductors passing from the sheave so that the conductors may be drawn through the two-holed polisher 51, whereupon 60 they are again twisted with the desired helix, in a manner to be presently described.

It will be observed that the twist just described is only incidental to the use of the sheave 45, which is employed to prevent the occurrence of a sharp bend in the conductors as they emerge from the polisher 39. If the sheave 45 should be 65 omitted the conductors would travel in an un-twisted condition from the polisher 39 to the polisher 51. The slight twist, however, which results from the use of the sheave 45 is immediately removed above the sheave and does not interfere 70 with feeding the conductors at a uniform tension and speed of travel to the actual twisting apparatus.

After emerging from the two-holed polisher 51 the untwisted pair of conductors 33 are drawn 75

over the periphery of a positively driven wheel 60 (Figs. 4 and 5) provided with two conductor receiving grooves 61 separated by a central tongue 62, one of the conductors passing into each of the grooves. The wheel 60 is secured to a rotatable shaft 65 having a bearing in the casting 47. The wheels 60, one for each of the pair of conductors 33 and 34, are positioned in horizontal alignment with their peripheries barely spaced apart with the vertical axis of the flier shaft 11 alined centrally therebetween, the adjacent inner portions of the wheels turning in a horizontal slot 66 formed in the casting 47 and extending from one side to the other side thereof. Secured to the shaft 65 is a bevel gear 67 which meshes with a bevel gear 68 fixed to the upper end of the universal shaft 55, which as hereinbefore described is driven from the motion of the yoke 16. The gear drive to the wheel 60 from the yoke 16 is such that the wheel makes two revolutions to one revolution of the yoke, the direction of its rotation being indicated by the arrows (Figs. 1, 2 and 5). The other wheel 60 over which the twisted pair of conductors 34 are drawn also makes two revolutions to one revolution of its associated yoke 17 but as hereinbefore described the yoke 17 is driven at a slower rate of speed than that of the yoke 16 due to the longer length of twist being formed in the conductors 34 than that of the conductors 33 and therefore the wheels 60 are driven at different speeds, the left hand wheel being rotated at a higher rate of speed than the right hand wheel.

In the continuous advancement of the two conductors 33 that portion thereof between the polisher 51 which is adjacent the apex of a cone-shaped path about which the conductors move while traveling upwardly, and the point of contact of the conductors with the periphery of the wheel 60, which is substantially at the apex of the cone-shaped path, will be continuously and uniformly twisted in a left hand direction as the polisher rotates about its own axis while revolving bodily with the flier about the axis of the flier shaft 11.

Reciprocable in a slot 71 formed in the wheel 60 at one side of the axis thereof is a finger 72, the slot being centered between the sides of the wheel (Fig. 4) and extending at its outer end through the tongue 62 which separates the two grooves of the wheel so that the finger may be advanced outside the periphery of the wheel as shown. The tongue 62 in addition to its being cut away to accommodate the described movement of the finger 72 is also cut away to form a gap 73 in the tongue for a certain distance above the finger 72, as viewed in Figs. 4 and 5, for a purpose to be described hereinafter. At one side the slot 71 extends, as indicated at 74, through the side of the wheel 60. Integral with the finger 72 and extending through the slot 74 of the wheel 60 is a guide boss 75 which rides on an endless stationary cam surface 78 formed in a depression in a cover plate 79 fixed at 80 (Figs. 2 and 4) to the casting 47, the slotted side surface of the wheel having a rotary sliding motion on the adjacent side surface of the cover plate. A compression spring 81 having its opposite ends engaged in depressions formed in the finger 72 and the wheel 60 constantly acts to hold the guide boss 75 of the finger riding against the cam surface 78.

In the continuous rotation of the wheel 60 the guide boss 75 of the finger 72 riding against the stationary cam surface 78 serves to successively advance and retract the finger in such a manner

that it is completely advanced just after it moves past the polisher 51 and is completely retracted to a position wherein its outer end is flush with the periphery of the wheel when it is in a substantially horizontal position pointing towards the vertical center line of the apparatus.

Formed in the casting 47 at its upper end and centered with the axis of the flier shaft 11 is an aperture 82 which at its lower end is open to the slot 66 (Figs. 2, 4 and 5). Carried in the aperture 82 is a one-hole polisher 85 secured in position at 86 (Fig. 4). The lower end of the polisher is reduced in diameter and extends downwardly into the slot 66 and between the wheels 60, the lower end thereof lying close to the peripheries of the wheels. The twisted pairs of conductors 33 and 34 immediately after passing from the grooves of the wheels 60 converge at the lower end of the one-hole polisher 85, pass through the hole of the polisher, the aperture 82 of the casting 47, and around the capstan 37, and thence to the take-up mechanism (not shown). In their passage from the grooves of the wheels 60 and through the hole of the polisher 85 the twisted pairs of conductors 33 and 34 are continuously and uniformly twisted together in a right hand direction to form a quad 87, due to the wheels 60 revolving bodily with the flier about the axis of the polisher which is centered with the axis of the flier.

It is believed from the foregoing description that the manner of continuously forming the pair twists in that portion of each pair of traveling conductors 33 and 34 between the polishers 51 and their engagement with the peripheries of the wheels 60 as the conductors are moved about the cone-shaped path and adjacent its apex and thereafter upon the pair twists moving from the engagement with the wheels being twisted together to form the quad twist will be clearly understood.

As hereinbefore described the wheel 60 makes two revolutions to one of the yoke 16, and the same relative to the two-holed polisher 51 which is continuously driven in synchronism with the yoke and therefore the finger 72 and the gap 73 in the tongue 62 of the wheel will pass the polisher 51 twice for each rotation of the polisher, or once for each 180° of polisher rotation. Thus it will be apparent that by synchronizing the rotation of the polisher 51 with the movement of the finger 72 and the gap 73 past the polisher, the successive cross-over points of the twisted conductors 33 produced by the polisher may be made to fall into the gap of the wheel 60. A complete twist of the conductors it will be obvious includes two crossings thereof, one being produced for each 180° rotation of the polisher 51. The advancement of the finger 72 associated with the left wheel 60 to the position shown in the drawings in timed relation with the crossing of the traveling conductors so that the finger is inserted between the conductors in timed relation with and immediately below the crossing point thereof insures that the cross-over point of the conductors will pass into the gap 73.

The relative positions of the two holes of the polisher 51 and the wheel 60 are such that when the crossing point of the conductors 33 is in tangential engagement with a surface 88 of the wheel along the gap 73 with the finger inserted between the conductors below the crossing point, the conductors between the polisher and finger will be substantially in a plane perpendicular to the plane of movement of the finger. As shown in the drawings, referring particularly to Fig. 4,

which shows the position of the polisher holes and the direction of rotation of the polisher, it will be noted that the conductors have not yet reached this parallel position. When the crossed pair of conductors 33 are positioned in the gap 13 their relative position is positively maintained and are thus carried into the one-hole polisher 88 where the twisted conductors 33 and the companion twisted conductors 34 are continuously and uniformly twisted together to form the quad 87. By continuously twisting the conductors of each pair and immediately thereafter maintaining the successive crossing points of the twists until they are very close to the point where the twisted pairs are twisted together to form the quad 87 the tendency of the relative positions of the conductors of each pair and of each twisted pair relative to the companion twisted pair to be disturbed is reduced to a minimum and consequently the length of twist of the conductors for each of the pairs of the quad will remain uniform.

Since in the operation of the apparatus, as hereinbefore described, the right hand wheel 68 is rotated at a slower rate of speed than the left hand wheel, due to the longer length of twist being formed in the conductors 34 than that of the conductors 33, the right hand wheel has not advanced in its rotation to the same angular position as its companion wheel 68 and consequently its finger 72 and the gap 73 have not reached the same position relative to the path of the conductors 34 as that shown for the finger 72 and the gap 73 of the left hand wheel 68.

In Figs. 6 to 9, inclusive, there is shown fragmentarily an embodiment of the twisting apparatus of this invention wherein polishers 108, corresponding in function to the polishers 51 of the apparatus previously described, are intermittently driven instead of continuously as are the polishers 51.

In this second embodiment, referring particularly to Fig. 6, there are employed a continuously rotating flier carrying a pair of rotary yokes, and a capstan, all driven in a manner similar to that of the first embodiment. Only such portions of the flier and one of the yokes is illustrated as are necessary to an understanding of the operation of the apparatus. An upper horizontal flier cross bar, which is fixed to a flier shaft 101, is indicated at 102 and journaled therein at its outer end is a stud shaft 103 fixed at its lower end to the upper end of a yoke 104, the upper end of the shaft extending a short distance above the upper surface of the bar. Secured to the upper end of the shaft 103 above the bar 102, as indicated at 105, is a circular shouldered centrally apertured plate 107 having formed in its peripheral surface at diametrically opposite points two gear teeth 108, the peripheral surface of the plate between the two teeth being smooth. Carried by the plate 107 within the aperture is a two-holed polisher 109. Fixed to the upper surface of the plate 107, as indicated at 110, is a bar 111 which at opposite ends is flush with the peripheral surface of the plate, the end surfaces of the bar each having formed therein three gear teeth 114, the center tooth at each end of the bar being aligned with the diametrically opposite teeth of the plate. At its center the bar 111 is enlarged and provided with an aperture which is centered with the aperture in the plate 107 and an aperture 115 in the shaft 103. In the operation of the apparatus conductors 116 and 117 are drawn from two supply reels (not shown)

carried by the yoke 104 and a companion yoke (not shown) at the opposite side of the flier shaft 101 and through the aligned apertures and the two-holed polishers 109 by the capstan (not shown).

Arranged at the right side of the plate 107 to mesh with the teeth 114 of the bar 111 is a pinion 118 having its opposite ends journaled at 121 and 122 in the flier cross bar 102 and a bracket 123 fixed to the flier shaft 101, respectively. The pinion 118 is formed with six teeth having the lower half of two diametrically opposite teeth cut away as indicated at 124 (Fig. 8). Secured at 125 to the upper end of the flier shaft 101 and rotating therewith is a casting 128. Fixed to 128 to the casting 128 is a bearing block 130. At diametrically opposite points the block 130 is formed with angularly arranged bearings within each of which is rotatably carried a shaft 131. The shaft 131 is operatively connected to a reduced upper end of the pinion 118 which extends from the bearing bracket 123 by a universal shaft 132. At its upper end the shaft 131 carries a gear 134 which meshes with a similar gear 135 formed on the lower end of a rotary holder 136 for the two-holed polisher 109, the holder being journaled in a bearing arranged at an angle similar to that of the bearing for the shaft 131, the bearing being formed on the casting 128. A collar 137 surrounding and fixed to the holder 136 within a slot in the casting 128 serves to maintain the holder from longitudinal movement. The two polisher holders 135 are formed with axial apertures 138 through which the conductors 116 and 117 pass after being threaded through the holes of the polishers 109, the conductors thereafter being threaded through the holes of the polishers 109, which it will be noted are arranged close to each other adjacent the apex of a cone-shaped path about which the conductors move while travelling upwardly and at either side of the axis of the flier shaft 101.

Secured in an axial depression 139 in the upper end of the casting 128 is a fixture 142 having its lower end bifurcated and carrying between the bifurcations and adjacent the upper ends of the converging polishers 109, which extend into the depression, a pair of aligned rollers 143, the peripheries thereof being spaced from the axis of the flier shaft 101. Carried in an aperture 144 formed in the upper end of the fixture 142 and centered with the axis of the flier shaft 101 is a pair of spaced one-hole polishers 145 secured in position at 146. The conductors 116 and 117 after passing through the polishers 109 converge and pass onto the peripheral surfaces of the rollers 143, which is the apex of the cone-shaped path about which the conductors move, and through the one-hole polishers 145 and around the capstan and thence to the take-up mechanism (not shown).

The operation of this last described embodiment of the invention, assuming that the flier shaft 101 and the yokes 104 bodily revolving therewith while rotating about their own axes are continuously driven in the direction of the arrows, as shown in Fig. 7, at predetermined speeds in accordance with the respective pair and quad twists being formed in the conductors 116 and 117, and that the capstan (not shown) is continuously drawing the conductors through the apparatus at the desired speed, is as follows:

During each complete rotation of the bar 111, which rotates continuously with the yoke 104 and the two-holed polisher 109, while revolving bodily about the axis of the flier shaft 101, the

set of three gear teeth at each end of the bar move into meshing relation with the upper portion of the six tooth gear pinion 118 and as each end of the bar moves past the pinion it is rotated 5 180°, which motion is transmitted by means of the universal shaft 132 and gears 134 and 135 to the two-holed polisher 100, so that the latter polisher is given two half turns, or 180° rotative movements, during each complete rotation of the 10 polisher 109. The pinion 118 is prevented from rotating during the periods in which the toothed ends of the bar 111 are not in driving engagement with the upper half of the pinion by the smooth peripheral surface of the circular plate 107 riding 15 in one or the other of the spaces formed by the removal of the two diametrically opposite teeth at the lower portion of the pinion 118 which is clearly shown in Fig. 8.

Thus as each pair of continuously traveling conductors 116 and 117 move upwardly between the two-holed polishers 109 and 100 which are continuously and intermittently rotated, respectively, while revolving bodily about the axis of the fier shaft 101, the pairs of conductors are 20 continuously being half twisted and then intermittently untwisted so that they may be drawn through the holes of the polisher 100. Simultaneously therewith the conductors of each pair as they pass through the polishers 100 and before 25 they engage the peripheries of the rollers 143 are twisted together with a desired lay or length of twist during the continued intermittent rotation of the polishers 100 about their own axes while revolving bodily with the fier about the axis of 30 the fier shaft 101. As the continuously traveling twisted pairs of conductors 116 and 117 pass from the peripheries of the rollers 143 and through the holes of the polishers 145 they are twisted together to form a quad 150 due to the rollers 35 revolving bodily with the fier about the axis of the polishers 145 which are centered with the axis of the fier. There is thus produced a quad- 40 ded cable 150 which consists of four parallel conductors, each pair of which is crossed successively at one-half of the desired lay or twist and such twist being immediately secured by the quad twist results in identical exposures of the four conductors to one another. Therefore, any tendency 45 of the relative positions of the conductors of each pair and of each twisted pair relative to the companion twisted pair to be disturbed is reduced to a minimum since the quad twist is produced immediately after the forming of the pair twists and consequently the length of the conductors 50 for each pair and of the pairs of the quad will remain the same.

In each of the embodiments of twisting apparatus of this invention described hereinbefore a plurality of strands may be twisted together into 55 a plurality of individual groups and the groups twisted together into a composite group in such a manner that the length and relationship of the strands of each group are maintained uniform without the use of a binding. The maintenance of a definite lineal relation between the strands constituting a pair is an essential requisite in the production of quadded cable having 60 the electrical characteristics desired.

While the invention has been described with 65 particular reference to quadded cable it will be understood that the invention is capable of other applications and that modifications can be made without departing from the spirit and scope of 70 the appended claims.

What is claimed is:

1. In a strand twisting apparatus, a plurality of rotatable elements, a plurality of sources of supply of strand material carried by each of said rotatable elements, means for moving the strands from said supplies and assembling them into individual groups and causing the strands of each group to move about a cone-shaped path and toward its apex, means adjacent said apex for rotating the strands of each group to twist them together on the slope of the cone-shaped path adjacent its apex, means for causing said supply carrying elements and said twisting means to rotate the same number of revolutions per unit of time, and means adjacent the apex for twisting said groups together to form a single group. 15

2. In a strand twisting apparatus, a plurality of rotatable elements, two sources of supply of strand material carried by each of said rotatable elements, means for moving the strands from said supplies and assembling them into individual pairs and causing the strands of each pair to move about a cone-shaped path and toward its apex, means adjacent said apex for rotating the strands of each pair to twist them together on the slope of the cone-shaped path adjacent its apex, means for causing said supply carrying elements and said twisting means to rotate the same number of revolutions per unit of time, and means adjacent the apex for twisting said pairs together 20 to form a quad. 25

3. In a strand twisting apparatus, means for continuously twisting a plurality of strands together, means intermittently movable into engagement with the strands immediately behind the cross over points of the strands for maintaining the relative positions of the twisted strands, and means for actuating said intermittently movable means in timed relation with the forming of the twists in the strands. 35

4. In a strand twisting apparatus, means for twisting a plurality of strands together to form a plurality of units, members intermittently movable into engagement with the strands of each unit immediately behind the cross over points of the strands for maintaining the relative positions of the strands of each unit, means for actuating said members in timed relation with the forming of the twists of each unit, and means for twisting said units together to form a single group. 40

5. In a strand twisting apparatus, a plurality of sources of supply of strand material, means for continuously drawing off strands from said supplies and twisting them together, members intermittently movable into an advanced position in engagement with the moving twisted strands immediately behind the cross over points thereof and movable longitudinally therewith for a predetermined distance for maintaining the relative positions of the twisted strands, and means for advancing and withdrawing said members in timed relation with the drawing off speed of the strands and the forming of the twists therein. 55

6. In a strand twisting apparatus, a plurality of sources of supply of strand material, means for continuously drawing off strands from said supplies and twisting them together, members movable into an advanced position between the moving twisted strands immediately behind the cross over points thereof and movable longitudinally therewith for a predetermined distance for maintaining the relative positions of the twisted strands, and means for advancing and withdrawing said members in timed relation with 70 the forming of the twists therein. 75

the drawing off speed of the strands and the forming of the twists therein.

7. In a strand twisting apparatus, a plurality of rotatable elements, two sources of supply of strand material carried by each of said rotatable elements, means for rotating said elements to twist together the strands from said supplies into individual pairs, means for causing the pairs to travel towards each other, means for twisting said pairs together to form a single group, said pair and group twist being effected in close proximity, members arranged between the points at which the pair and group twists occur intermittently movable into position between the strands of

each pair immediately behind the cross over points of the strands for maintaining the relative positions of the strands of each pair, and means for actuating said members in timed relation with the forming of the twists of each pair.

8. In a strand twisting apparatus, a plurality of sources of supply of strand material, means for continuously drawing off strands from said supplies and twisting them together, rotatable grooved means in the grooves of which the portions of each moving strand between successive cross over points of the twisted strands travel, said rotatable grooved means having a gap in the peripheral portion between the grooves thereof in which successive cross over points of the twisted strands travel for maintaining the relative positions of the twisted strands, and means for rotating said grooved means in timed relation with the drawing off speed of the strands and the forming of the twists therein.

9. In a strand twisting apparatus, a plurality of sources of supply of strand material, means for continuously drawing off strands from said supplies and twisting them together, a wheel having two peripheral strand guiding grooves in which portions of each moving strand between successive cross over points of the twisted strands travel, said wheel having a gap in the peripheral portion between the grooves thereof in which successive cross over points of the twisted strands travel for maintaining the relative positions of the twisted strands, and means for rotating said wheel in timed relation with the drawing off speed of the strands and the forming of the twists therein.

10. In a strand twisting apparatus, a plurality of sources of supply of strand material, means for continuously drawing off strands from said supplies and twisting them together, a wheel having a plurality of peripheral strand guiding grooves

in which portions of each moving strand between successive cross over points of the twisted strands travel, said wheel having a gap in the peripheral portion between the grooves thereof in which successive cross over points of the twisted strands travel, an element intermittently movable into position between the moving twisted strands immediately behind successive cross over points thereof and traveling therewith for a predetermined distance for maintaining the relative positions of the twisted strands, and means for actuating said element in timed relation with the drawing off speed of the strands and the forming of the twists therein.

11. In a strand twisting machine, means for drawing strand material from a plurality of sources, means for mounting said sources for rotation about an axis extending in the direction of withdrawal of the strands, means located at a point remote from said sources for rotating the strands about each other to twist them, and means causing the last mentioned means and said sources to rotate the same number of revolutions per unit of time.

12. In a strand twisting machine, means for drawing strand material from a plurality of sources, means for mounting said sources for rotation about an axis extending in the direction of withdrawal of the material, means rotatable about said axis in unison with the rotation of said sources having apertures for individually guiding each of the strands while being drawn from said sources, means located at a point remote from said sources for rotating the strands about each other to twist them, and means causing said guiding means and said twisting means to rotate the same number of revolutions per unit of time.

13. In a strand twisting machine, means for drawing material from a plurality of sources to form a group, means for mounting said sources for rotation about an axis extending in the direction of withdrawal of the strands, means located at a point remote from said sources for rotating the strands about each other to twist them, means for causing the last mentioned means and said sources to rotate the same number of revolutions per unit of time, and means for twisting another group of strands, guiding them to the twisted strands first mentioned and twisting the two groups together at a point near said first twisting means.

ROLAND R. NYDEGGER.
